UNITED STATES PATENT OFFICE

2,491,019

LABEL MOISTENER

John F. Werker, Vincennes, Ind.

Application December 17, 1947, Serial No. 792,193

1 Claim. (Cl. 91—51)

1

This invention relates to a moistening device, and more particularly to a device for moistening gum labels.

An object of the invention is to provide an absorbent roller means upon which the label is pressed for the moistening thereof, and means for pressing the label on the roller to insure perfect moistening of the label.

Another object of the invention is to provide a suitable reservoir for the absorbent roller, so that the roller is maintained in a moistened condition at all times.

A further object of the invention is to provide a device that is simple in construction, efficient in operation and inexpensive to manufacture.

With the above and other objects and advantages in view, the invention consists of the novel details of construction, arrangement and combination of parts more fully hereinafter described, claimed and illustrated in the accompanying drawings in which:

Figure 1 is a top plan view of an embodiment of the invention;

Figure 2 is a front elevational view of Figure 1;

Figure 3 is an end elevational view of Figure 1;

Figure 4 is a vertical sectional view on the line 4—4 of Figure 3;

Figure 5 is a vertical, sectional view on the line 5—5 of Figure 2 and

Figure 6 is a perspective view of the label guide.

Referring more in detail to the drawings, the reference numeral 10 is used to generally designate the label moistener embodying the invention.

The moistener comprises a body having a base plate 11, which is rectangular in cross-section, and may be made of wood, metal or any other suitable material. Secured to the base plate 11, in vertical relation thereto, are the relatively spaced side plates 12 and 13 respectively, which are bridged at their front ends by the cross plate 14. The cross plate 14 is flush with the forward edge of the base plate 11, and the vertical end edges of the side plates 12 and 13 are flush with the rear edge of the base plate 11. It will be seen from the drawings, however, that the side plates are inset with regard to the end edges of the base plate 11.

The side plates, for their entire height, are freely open at their rear edges, but a cross bar 15 is secured to the top edges of the side plates, so that the side edges of the bar and the end edges of the side plates, are in vertical alinement with each other.

2

Adjacent the forward edges of the side plates 12 and 13, there is provided in each plate, a semi-circular recess 16, which is adapted to receive the shaft 17. The shaft 17 is thus rotatably mounted on the side plates, and extends in parallel longitudinal relation to the base plate 11.

The shaft 17 is provided on one end with a knob handle 18, whereby the shaft is rotated. Secured to the shaft 17 intermediate of the side plates 12 and 13, is a solid roller 19, and on this roller 19 is sleeved an absorbent roller or sleeve 20. The roller 20 is moistened by capillary attraction of the water 21 placed in a pan 22 directly below the roller and resting on the base plate 11. Therefore, as the shaft is rotated, the roller 21 is constantly moistened.

The side plate 12 has a bearing plate 24 secured thereto by fasteners 25, and the bearing plate 24 engages the free end of shaft 17 to retain the shaft in its relative position with relation to the roller 20 and pan 22.

The side plate 13 also has a bearing plate 26 secured thereto by fasteners 27, but this plate has a recess 28 conforming to the shape of the recess 16 in the plate 13.

Secured to the cross bar 15, at right angles thereto, by fasteners 29 are the spring bands 30 and 31 respectively. These bands extend in parallel relation to the side plates 12 and 13, and are mounted slightly inwardly of the side plates.

The bands extend almost to the forward end edges of the side plates, and are adapted to exert downward pressure on the label guide 32, which is slidably mounted on the bands 30 and 31 respectively.

The guide 32 is in the form of a comb, as shown in Figure 6, having the back bar 33 on which are formed the forwardly extending parallel related and relatively spaced teeth 34.

The teeth are of normal formation, and rest on the roller 22.

The back 33 of the guide 32 is provided with open ended slots 35 which slidably engage the bands 30 and 31, respectively. The portion of the back 33 forming the top of the slots is cut away, as shown at 36, to prevent the back from binding on the bands.

The guide is made of a clear plastic and prevents the label from getting wet on the top thereof as it passes under the guide.

In use, the label is fed from the forward side of the label indicator 10, and the label passes under the guide as the shaft 17 is turned,

by means of the knob 18. As the shaft 17 is rotated, the label will pass outwardly of the moistener between the side plates, and under the cross bar 15.

The moistener is efficient, easy to operate and will effectively moisten the label, as it passes over the roller, by means of the downward pressure of the guide on the label caused by the tension thereon of the bands 30 and 31.

It is believed that from the foregoing description, the operation and construction of the moistener will be apparent to those skilled in the art, and it is to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

A label moistener of the type described, comprising a base plate, a pair of relatively spaced side plates secured to said base plate in vertical relation thereto, a cross plate secured at its opposite ends to one of the vertical ends of each of said side plates in engagement with the base plate and flush with the longitudinal edge thereof, a shaft journaled on the upper longitudinal edges of said side plates, an absorbent roller on said shaft, a liquid containing means on said base plate below said roller and rearwardly of said cross plate so that liquid placed

in said container will be in contact with said roller, a cross bar secured at its opposite ends to the upper longitudinal edges of said side plates adjacent the ends thereof remote from ends secured to the cross plate, a pair of spring bands secured at one of their ends to said cross bar adjacent the outer ends thereof, and extending in a horizontal plane over said roller in spaced relation to each other and in parallel relation

- 5 to the ends of the roller, a guide member having open ended slots therein adjacent the opposite ends thereof and the slots in said member adapted to engage said spring bands so that said guide member is mounted on said spring bands for sliding movement thereon, relatively spaced teeth members on said guide member adapted to extend inwardly of the ends of said spring bands to engage said roller to effectively force a label to be moistened into contact with said roller.
